UNITED STATES PATENT OFFICE.

ALFRED LEANDER RIGGS, OF EBENSBURG, PENNSYLVANIA.

STEAM-TRAP.

No. 901,190.

Specification of Letters Patent.

Patented Oct. 13, 1908.

Application filed January 9, 1908. Serial No. 409,930.

To all whom it may concern:

Be it known that I, ALFRED LEANDER RIGGS, a citizen of the United States, and a resident of Ebensburg, in the county of Cambria and State of Pennsylvania, have invented a new and Improved Steam-Trap, of which the following is a full, clear, and exact description.

The invention relates to steam traps, such as shown and described in the Letters Patent of the United States, No. 844,958, granted to me February 19, 1907.

The object of the present invention is to provide a new and improved steam trap, arranged to insure a positive and easy working of the valve controlling the inflow and the discharge of the water, and to positively hold the valve locked in one position until the trap is accurately filled with a predetermined quantity of water, and to hold the valve locked in its other position until the intended quantity of water has been discharged.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a side elevation of the improvement, parts being broken away; Fig. 2 is an enlarged transverse section of part of the improvement, the section being on the line 2—2 of Fig. 3; Fig. 3 is an enlarged side elevation of part of the improvement, the cover thereof being removed; Fig. 4 is a similar view to that shown in Fig. 3, the view showing the disk valve in a different position, part of the disk valve being broken away; Fig. 5 is a sectional side elevation of part of the improvement, on the line 5—5 of Fig. 6, and Fig. 6 is a sectional plan view of part of the improvement, on the line 6—6 of Fig. 5.

In the receptacle A of the trap is arranged a float B having its stem B' secured on the inner end of a rock shaft C' that supports a lever C, the said shaft C' being journaled in a suitable bearing D screwed or otherwise secured in the front wall of the receptacle A. The inner end of the bearing D is provided with a conical seat D' engaged by the correspondingly - shaped inner end C² of the

shaft C', to insure a tight joint between the shaft C' and the bearing D, the shaft C' being pressed in an outward direction by a spring C³, to hold the end C² in firm contact with the seat D'. When the water rises and falls in the receptacle A, the float B rises and falls with it, thus imparting a swinging motion to the lever C, which is thus controlled in its movement by the float B.

The lever C is connected at its lower free end by a spring E with an arm F, secured to the outer end of the stem G' of a three-way valve G, for controlling the flow of the water of condensation from a supply pipe H to the receptacle A and for controlling the outflow of the water from the receptacle to a discharge pipe I, employed for conducting the water to a suitable place of discharge.

The three-way valve G has its cylindrical casing G² bolted or otherwise secured to the outside of the receptacle A near the lower end thereof, and the said valve casing G² is provided with a valve seat G³ having an inlet port a, a discharge port b and a connecting port c, of which the inlet port a connects with the supply pipe H (see Fig. 6), the outlet port b connects with the discharge pipe I, and the connecting port c communicates with a channel d (see Fig. 2) formed on the side of the receptacle A, and opening into the latter at or near the bottom thereof, to insure a complete discharge of the water from the receptacle A, as hereinafter more fully described.

On the valve seat G³ is seated a disk valve G⁴ having an elongated inlet port e, a connecting port f and a discharge cavity g formed on the rear face of the disk valve G⁴. The inlet port e is at all times in register with the inlet port a, the connecting port f is adapted to register with the connecting port c, and the cavity g is adapted to connect the ports b and c with each other, at the time the port f is out of register with the port c (see Fig. 4), the cavity g being out of register with the connecting port f at the time the ports f and c are in register with each other. The stem G' of the disk valve G⁴ is mounted to turn in the cap G⁵ closing the outer end of the valve casing G², and spaced from the disk valve G⁴ to allow the water to pass from the inlet pipe H by way of the ports a and e into the space formed between the cap G⁵ and the disk valve G⁴. The water flows from this space into the receptacle A whenever the ports f and c are in register with

- each other, as illustrated in Figs. 2 and 3. The water flows out of the receptacle A into the discharge pipe I whenever the disk valve G⁴ is turned into the position shown 5 in Fig. 4, that is, when the ports b and c are connected with each other by the cavity g. The hub of the disk valve G⁴ is provided with a diametrical recess G⁶, engaged by a pin G⁷, secured on the valve stem G⁵, so 10 that when the latter is turned a turning motion is given to the disk valve G⁴. On the stem G⁵ is secured a collar G⁸ seated on the inner face of the cap G⁶ so as to form a tight joint between the cap and that portion 15 of the stem G⁵ journaled in the cap G⁶. A spring J seated in the valve casing G² presses against the inner end of the valve stem G⁵, to hold the collar G⁸ in firm contact with the cap G⁶, to prevent leakage.
- 20 The swinging motion of the arm F is limited between stops K and K', formed or secured on the valve casing G². The free end of the arm F is provided with a transversely-extending locking pin F', preferably 25 made triangular in cross section, and adapted to be alternately engaged by locking arms L and L' adjustably secured on a transverse pin N attached to the float-controlled lever C, as illustrated in Figs. 1 and 2.
- 30 The arms L and L' are fastened in place on the pin N by nuts N', N² screwing on the pin N, the arms L and L' abutting against opposite faces of a collar N³ formed on the pin N, as plainly shown in Fig. 2. The 35 upper end of the lever C is connected by an arm O with a movable part P' of a water meter P of any approved construction, so that the water meter registers the amount of water passing through the trap.
- 40 The operation is as follows: When the several parts are in the position shown in Figs. 1, 2, 3 and 6, then the receptacle A is cut off from the discharge pipe I, but is connected with the supply pipe H, so that 45 the water of condensation flows into the receptacle A by way of the three-way valve G. As the water rises in the receptacle A, the float B rises with it, and in doing so imparts a swinging motion to the lever C, 50 whereby the locking arm L is finally moved into engagement with one side of the pin F', to hold the arm F in its extreme left-hand position, resting against the stop K. The locking arm L remains in contact with 55 the pin F' until the lever C has passed a central position, and when the desired amount of water has accumulated in the receptacle A, the locking arm L disengages the pin F', and the spring E, which was put under tension by the swinging of the lever C, 60 now acts on the release arm F, so as to swing the latter quickly over against the stop K' into the position shown in dotted lines in Fig. 1. When this takes place the disk 65 valve G⁴ is turned from the position shown

in Fig. 3 to that shown in Fig. 4, whereby the ports c and f are disconnected from each other and consequently water ceases to flow into the receptacle A. At the same time the port c is connected with the port b by the cavity g, so that the water now flows out of the receptacle A by way of the channel d, port c, cavity g and port b, which latter conducts the water to the discharge pipe I. By having the channel d arranged as described the water is almost completely siphoned out of the receptacle A. When the float B falls with the outflowing water the arm L' comes in contact with the other side of the pin F' to hold the arm F locked in its right-hand side position. The arm L' remains in contact with the pin F' until the water has been discharged from the receptacle A and the float B has fallen to its lowermost position and moved the lever C past its central position. When the lever C has passed the central position the arm L' releases the pin F', so that the spring E now immediately and quickly throws the arm F over against the stop K into the position shown in full lines in Figs. 1 and 2. When this takes place the disk valve G⁴ is returned to its original position indicated in Figs. 2, 3 and 6, that is, the receptacle A is cut off from the discharge pipe I, while the pipe H is connected with the receptacle A to refill the same.

By having the locking arms L and L' arranged and coacting with the pin F', as described, it is evident that the float lever C can safely pass its central position and place the spring E under tension without danger of accidentally turning the valve G too soon. Thus by the arrangement described the amount of water to be discharged from the receptacle can be predetermined with great accuracy and the amount registered by the meter P. It will also be noticed that the water of condensation or the steam flowing into the valve casing G² holds the disk valve G⁴ firmly to its seat G³, to prevent leakage of water in the valve from the supply pipe H to the discharge pipe I.

Having thus described my invention, I claim as new and desire to secure by Letters Patent:

1. A steam trap provided with a receptacle, a valve for controlling the inflow and outflow of the water to and from the said receptacle, a float-controlled lever, and a locking device carried by the lever for temporarily locking the valve against movement until the desired amount of water has accumulated in the receptacle or the quantity of water has been discharged from the receptacle.

2. A steam trap, comprising a vessel, a valve for controlling the flow of the water to and from the said vessel, an arm on the said valve for operating the same, a float-

controlled lever connected with the said arm and provided with locking arms adapted to engage the said valve arm to hold the latter locked in either of two positions.

5 3. A steam trap, comprising a vessel, a valve for controlling the flow of the water to and from the said vessel, an arm on the said valve for operating the same provided with a stop pin, a float-controlled lever, a 10 spring connecting the said float-controlled lever with the said valve arm, and locking arms attached to the said float-controlled lever and adapted to alternately engage the said stop pin.

15 4. A steam trap, comprising a vessel, and a float-controlled valve having a valve casing provided with a valve seat having a water inlet port, a water discharge port, and a connecting port connected with the interior of 20 the vessel, and a disk valve oscillating on the said valve seat and having a water inlet port, a filling port and a cavity on its underside, the said water inlet port registering at all times with the water inlet port in the 25 valve seat, the said filling port being adapted to register with the said port leading to the vessel and the said cavity being adapted to connect the said water discharge port with the said port leading to the vessel.

30 5. A steam trap, comprising a vessel, a float rising and falling with the water in the said vessel, a lever controlled by the said float, a spring connected with the said lever, and a valve having a valve casing provided 35 with a valve seat having an inlet port for the water of condensation, a water outlet port, and a connecting port leading to the vessel, a disk valve on the said valve seat having ports for register with the said inlet 40 port and the said vessel-connecting port, and

a cavity for connecting the said vessel port with the outlet port, and an arm on the stem of the said valve connected with the said spring.

6. A steam trap, comprising a receptacle, 45 a valve for controlling the flow of the water to and from the said receptacle, an arm on the said valve for operating the same, a bearing secured in the front wall of the receptacle and having a conical seat at its 50 inner end, a shaft journaled in said bearing, the inner end of the shaft having a conical portion engaging said seat, a float arranged in the receptacle and having its stem connected with the inner end of said shaft, a 55 lever supported on the outer end of said shaft, a spring for holding the conical portion of the shaft in engagement with the seat, a spring connecting the lower end of said lever with the arm on the valve, and a locking device for the said arm of the valve, the locking device being carried by said lever.

7. A steam trap, comprising a receptacle, 65 a valve for controlling the flow of water to and from the said receptacle, an arm on the said valve for operating the same, means for limiting the swinging motion of the arm, a float controlled lever connected with the said arm, a stop pin carried at the free end 70 of said arm, and locking arms adjustably secured to the said lever, and adapted to engage the said stop pin.

In testimony whereof I have signed my name to this specification in the presence of 75 two subscribing witnesses.

ALFRED LEANDER RIGGS.
